UNITED STATES PATENT OFFICE

MAURICE E. BOSLEY, OF CHICAGO, ILLINOIS, ASSIGNOR TO THE D. W. BOSLEY COMPANY, OF CHICAGO, ILLINOIS, A CORPORATION OF ILLINOIS

WEATHER STRIP

Application filed December 27, 1926. Serial No. 157,089.

The present invention relates to an improvement in weather-stripping or strips for sealing the space between movable closures such as windows and doors.

5 The main object of the invention is the provision of a waterproof weather-strip which will completely seal the jointure in which it is positioned, which will withstand a maximum amount of wear, which will have 10 a neat appearance in use and which may be easily and economically manufactured.

Another important object of the invention is the provision of a weather-strip proof 15 against deterioration by rotting of constituent materials.

Numerous other objects of the invention will be apparent as it is better understood from the following description, which, taken 20 in connection with the accompanying drawings, discloses a preferred embodiment thereof.

Referring to the drawings:

Figure 1 is an elevation of a weather-strip embodying my invention, parts of which are 25 shown broken away to disclose the interior construction thereof; and

Fig. 2 is a section taken substantially on line 2—2 in Fig. 1.

The use of weather-stripping is thought to 30 be sufficiently well known to need no explanation and a description thereof will not be made.

To illustrate my invention I have shown 35 a weather-strip consisting of a core 11 and an enclosing sleeve 12. The core is of cotton or similar resilient packing material and consists of a sufficient number of strands twisted to make a rope of desired diameter. The sleeve 12 is a strip of material treated to 40 render the fabric thereof moisture-proof, and is of sufficient width that when it is closely wrapped around the core 11, the edge strips 13 and 14 of sleeve 12 overlap and are arranged adjacent to and parallel with each 45 other to form an outstanding flange 12'. A strip of material 15 is folded longitudinally at 15' and embraces the outstanding edges 13 and 14. The sides 16 and 17 of the folded strip 15 lie parallel with and exteriorly adjacent to the extending flange 12'. The edges

18 and 19 of the sides 16 and 17 are folded inwardly as shown in Fig. 2, and a seam 20 passes therethrough and fastens the parts together at the base of the outstanding flange. The seam 20 joins the edges 13 and 14 of the 55 sleeve 12, and so encloses the core 11 within its sleeve. The seam also secures the folded strip 15 to the flange and provides a sturdy web 23 projecting from the body of the weather-strip. Other seams 21 and 22 parallel with seam 20 are provided in the web 60 as shown to give added strength.

The projecting web 23 is of quadruple thickness comprising strips 13, 14, 16 and 17 stitched together by seams 20, 21 and 22. The 65 outer strips 16 and 17 are integral with each other and a neat folded appearance is presented at the outer edge of the web. The edges 18, 19 of strip 15 are folded under and stitched in place for the sake of appearance 70 and to give extra strength at the base of the web. This construction provides an unusually durable web for securing the strip in operative position to a closure member and creates maximum strength where it is most 75 needed.

It is thought that the invention and many of its attendant advantages will be understood from the foregoing description, and it will be apparent that many changes may be 80 made in the form, construction and arrangement of the parts without departing from the spirit and scope of the invention or sacrificing all of its material advantages, the form herein described being merely a preferred 85 embodiment thereof.

I claim:

1. Weatherstripping comprising, a main body portion embodying a core of compressible packing material and a substantially tubular core covering made of waterproofed pliable fabric material enclosing said packing material, and a substantially self-sustained attaching flange laterally projecting from said main body portion, said flange being made 90 wholly of fabric material like said core covering and embodying, inside plies provided by laterally projecting integral portions of said core covering, and a covering strip made 95 of material like said core covering, folded 100

at its outer edge to provide outside plies of said flange which enclose completely said inside plies, and infolded between the outside and inside plies at the inner flange edge, to provide reinforcement adjacent said main body portion, and rows of stitching uniting the several plies at the reinforced and other portions of said flange.

2. Weatherstripping comprising, a main body portion embodying a core of compressible packing material and a substantially tubular core covering made of pliable fabric material enclosing said packing material, and a substantially self-sustaining attaching flange laterally projecting from said main body portion, said flange being made wholly of fabric material like said core covering and embodying, inside plies provided by laterally projecting integral portions of said core covering, and a covering strip made of material like said core covering, folded at its outer edge to provide outside plies of said flange which enclose completely said inside plies, and infolded between the outside and inside plies at the inner flange edge, to provide reinforcement adjacent said main body portion, and rows of stitching uniting the several plies at the reinforced and other portions of said flange.

3. Weatherstripping comprising, a main body portion embodying a core of compressible packing material and a substantially tubular core covering made of pliable fabric material enclosing said packing material, and a substantially self-sustaining attaching flange laterally projecting from said main body portion, said flange being made wholly of fabric material like said core covering and embodying, inside plies provided by laterally projecting integral portions of said core covering and a covering strip made of material like said core covering folded at its outer edge to provide outside plies of said flange which enclose completely said inside plies, and refolded at the inner flange edge, to provide reinforcement adjacent said main body portion, and stitching uniting the several plies of said flange.

4. Weatherstripping comprising, a main body portion embodying a core of compressible packing material and a substantially tubular core covering made of pliable fabric material enclosing said packing material, and a substantially self-sustaining attaching flange laterally projecting from said main body portion, said flange being made wholly of fabric material and embodying, inside plies provided by laterally projecting portions of said core covering, and a fabric covering strip folded at its outer edge to provide outside plies of said flange which enclose completely said inside plies, and infolded between the outside and inside plies at the inner flange edge, to provide reinforcement adjacent said main body portion, and

stitching uniting the several plies of said flange.

5. Weatherstripping comprising, a main body portion embodying a core of compressible packing material, and a substantially tubular core covering made of pliable fabric material enclosing said packing material, and a substantially self-sustaining attaching flange laterally projecting from said main body portion, said flange being made wholly of fabric material embodying, inside plies provided by laterally projecting integral portions of said core covering, and a fabric covering strip secured to said inside plies and folded at its outer edge to provide outside plies of said flange which enclose completely said inside plies, and refolded at the inner flange edge to provide reinforcement adjacent said main body portion.
